UNITED STATES PATENT OFFICE.

THOMAS WARREN TALIAFERRO, OF OMAHA, NEBRASKA.

APPARATUS FOR SMOKING MEAT PRODUCTS.

SPECIFICATION forming part of Letters Patent No. 650,877, dated June 5, 1900.

Application filed March 28, 1898. Serial No. 675,379. (No model.)

To all whom it may concern:

Be it known that I, THOMAS WARREN TALIAFERRO, residing at Omaha, in the county of Douglas and State of Nebraska, have invented 5 certain useful Improvements in Apparatus for Smoking Meat Products; and I do hereby declare that the following is a full, clear, and exact description of the invention, such as will enable others skilled in the art to which it

10 appertains to make and use the same, reference being had to the accompanying drawings, which form a part of this specification.

This invention has relation to a new and 15 novel improvement in apparatus for expeditiously handling and smoking meat products in curing the same.

The object of my invention is to provide a 20 simple apparatus within which meat products and other food compounds are to be smoked,

25 as will be described more fully hereinafter.

In the accompanying drawings, Figure 1 shows a central sectional view of an apparatus or smoke-house embodying my invention. Fig. 2 shows an enlarged broken detail 30 of one of the hangers as used in my invention. Fig. 3 shows a sectional view of one of the hanger-bars as used in my invention. Fig. 4 shows an enlarged end detail disclosing the arrangements of the rail 35 and trolley as used in my devices, while Fig. 5 shows a top view of one of the hanger-bars.

My invention comprises, essentially, a house 40 embodying four retaining-walls 1 and 2 and a top or roof 8, while below I provide an ordinary combustion-chamber, below which is positioned an ash-pit, as is usual, ordinary doors 5 being provided to cover the necessary feed-openings to the combustion-chamber and ash-pit. This structure above the fire-pot, 45 which is divided from the ash-pit by means of an ordinary grate 10, is provided with a series of grate-floors C, which floor-gratings may be of wood, iron, or other any suitable material, so that my smoking apparatus or house

50 is divided into a series of superposed chambers x, into which chambers extends the trolley-racks upon which are hung the products to be smoked. Above the upper chamber are suitable escape-ways 7, which permit a 55 proper draft, as is usual in devices of this class. Each of the chambers x is provided at any suitable point with a suitable air-

tight door, the upper chamber in Fig. 1 alone shown as provided with a door which is identified by the numeral 9. Within each of 55 these smoke-chambers and from the roof-gratings or ceiling-grating C are one or more trolley-rails A, which are in cross-section in shape of the letter J and which are secured to the grating C by means of suitable stringers B, as is shown in the drawings.

In Fig. 1 I have shown my smoking-house or smoking apparatus as forming part of an ordinary packing-house provided with the rooms y, this adjoining structure being provided with a suitable roof and from which extend one or more of the J-shaped trolley-rails directly into the upper smoking-chamber, so that the products may be railed from the adjoining chambers directly into the 70 smoking-house, or vice versa.

The hangers which I use in my device are of peculiar construction and comprise an upper trolley embodying the two horizontal bars 20 and 28, and to the bars 21 are secured the 75 trolley-wheels 23, as is clearly shown. Extending to the lower bar 28, which is secured to the bars 21 by any suitable means, is the swiveled hook 24, which hook engages a central loop forming part of the main supporting-rod 25. At each end this rod is provided with a suitable opening, through which the two end bars 26 pass, as is clearly shown in Fig. 2. Working upon these rods 26 are a series of pipe-sections 35, and between these 85 pipe-sections are held the hanger-bars K, from which bars extend upon opposite sides a series of preferably iron supporting-pins a, from which the products are suspended. The pipe-section 35, as well as the hanger-bars K, 90 being removable are held upon the bars 26 by means of ordinary nuts, which thread upon these bars 26. From this it will be seen that the hangers may be readily adjusted, as they are permitted a rotary movement by virtue 95 of the swivel-hook 25. To further strengthen the framework, I provide an additional bar 36, which secures the upper hanger-bar K to the supporting-bar 25, as is shown in Fig. 1.

In the usual method of smoking meat products the smoking-chambers are provided with a series of bars removably held therein and from which the products are suspended by means of short bars. Considerable time is

required in placing the products in the usually-constructed smoke-house, and, further, a great deal of the space is taken up by the cross-bars, which are usually of wood, and, as they collect all the waste particles which drop from the products, are objectionable. Further, the old method requires the labor of from two to four men to remove and pass along the products both in hanging them into the smoke-house and removing them. By means of my device the hangers can be taken to any convenient point within the building and neatly and compactly packed and hung with the meat products to be smoked. The carriers or hangers are then pushed along the track and into the house, where they are swung one against the other in a compact form, as illustrated in the upper section of Fig. 1, where two chambers are shown as partly provided with my improved trolley-hangers loaded with meat products to be smoked, these products being marked Δ in the drawings.

Now, having thus described my said invention, what I claim as new, and desire to secure by United States Letters Patent, is—

1. The combination of adjacent compartments and a rail or guide extending from one compartment to the other, a trolley adapted to travel on said rail or guide, and a rack including vertical side rods, horizontal rods having suspending devices, means for spacing the horizontal rods on the side rods and means for swiveling the rack to the trolley, and means for passing products of combustion through one of said compartments for smoking the products suspended from the rack.

2. The combination with a suspended rail or track and a trolley adapted to travel thereon, of a rack including vertical rods or bars and a trussed rod or bar connecting them at

the upper end, a swivel connection between the trussed bar and the trolley, horizontal rods or bars having their ends mounted on the vertical side rods, and provided with means for the attachment of articles to be suspended, and means for spacing the horizontal rods or bars.

3. The combination with a suspended rail or track and a trolley adapted to travel thereon, of a rack including vertical side rods, a trussed bar or rod connecting the upper ends of the side rods, a swivel connection between the trussed rod and the trolley, spacing sleeves loose on the side rods and horizontal bars or rods having their ends disposed between adjacent sleeves, and mounted on the side rods, and laterally-extending rods carried by the horizontal bars or rods and from which articles are to be suspended.

4. A meat-suspending rack including vertical rods, horizontal rods or bars removably connecting at their ends with the vertical rods, suspending devices carried by the horizontal rods or bars, removable loose sleeves on the vertical rods and spacing the horizontal rods, and means for suspending the rack from a point above.

5. The combination in a smoke-house of the following instrumentalities to wit: the rail A, a trolley-carriage comprising the bars 20 and 21, and the wheels 23, the swivel-hook 24, and a hanger depending from said hook comprising the rods 26, the pipe-sections 35, the cross-bars K, provided with the bars a, all arranged substantially as and for the purpose set forth.

In testimony whereof I affix my signature in presence of two witnesses.

THOMAS WARREN TALIAFERRO.
